[57] CLAIM

[**] Term: 14 Years

The ornamental design for an electronic control module enclosure, as shown and described.

[21] Appl. No.: 272,261

DESCRIPTION

[22] Filed: Nov. 15, 1988

FIG. 1 is a perspective view of an electronic control module enclosure showing our new design, the broken lines around the perimeter are for illustrative purposes only and represent functional electronic connector pins; FIG. 2 is a left side elevational view thereof; FIG. 3 is a front elevational view thereof; FIG. 4 is a right side elevational view thereof; FIG. 5 is a rear elevational view thereof; FIG. 6 is a bottom view thereof; and FIG. 7 is a top plan view thereof.
